UNITED STATES PATENT OFFICE

JOSEPH M. JENSEN, OF LOS ANGELES, CALIFORNIA, ASSIGNOR TO WESLEY M. BARRETT,
OF LOS ANGELES, CALIFORNIA

CLOSURE FOR A BOTTLE OR THE LIKE

Application filed November 28, 1928. Serial No. 322,383.

This invention has to do with a closure for a bottle, or the like, and it is an object of the invention to provide a construction particularly applicable to the crown type of bottle 5 cap.

It is a general object of the present invention to provide a bottle cap with a simple, inexpensive and effective means in the form of a valve device whereby material can be dispensed through the cap without detaching the cap from a bottle, or the like, to which it 10 may be applied.

An important object of the invention is to provide a device of the character mentioned 15 which is of simple, inexpensive construction and at the same time dependable in operation.

The device of the present invention, when in closed position, is tightly sealed and is such as to hold pressure in the container to which 20 the cap is applied. When the device is open material can be freely dispensed from the bottle or container.

A further object of the invention is to provide an improved, practical and inexpensive 25 means of finishing the relatively moving or cooperating parts of the valve device so that they can be of inexpensive manufacture and at the same time fit tightly together so that the device is tight and dependable in operation.

30 It is a further object of the present invention to provide a device of the character described having a minimum number of parts each of which is extremely simple and inexpensive of manufacture making the device 35 commercially practical.

The various objects and features of the invention will be best and more fully understood from the following detailed description 40 of a typical form and of typical applications of the invention, throughout which description reference is had to the accompanying drawings, in which:

Fig. 1 is a side elevation of the neck portion of a bottle showing a typical crown cap 45 provided with the present invention applied thereto. Fig. 2 is a view similar to Fig. 1 showing a detachable form of crown cap embodying the present invention. Fig. 3 is an enlarged detailed sectional view illustrating 50 the device shown in Fig. 1 showing it in

closed or sealed position. Fig. 4 is a view similar to Fig. 3 showing the device open or in dispensing position. Fig. 5 is a detailed transverse sectional view taken as illustrated by line 5-5 on Fig. 3. Fig. 6 is a plan elevation taken as indicated by line 6-6 on Fig. 4, and Fig. 7 is a detailed sectional view of a portion of the device being a view taken as indicated by line 7-7 on Fig. 4.

The present invention is, in its broader aspects, applicable to various constructions, however, in the preferred and commercial embodiment of the invention it is applied to the crown type of bottle closure, this type of closure being the most common and popular type of closure in general use.

In practice crown type bottle closures or caps are used on bottles containing a variety of materials, for instance they are commonly used on bottles containing beverages of various kinds, and on bottles containing various household commodities.

The present invention is useful as applied to caps used on bottles containing beverages, particularly carbonated beverages. In the case of carbonated beverages the present invention can be used in dispensing the beverages so that pressure generated within the container discharges the fluid at a high velocity in a manner to effectively mix with other beverages

into which it may be discharged. In the case of various household commodities such as flavorings, sauces, etc., the invention can be applied to advantage to dispense such materials in relatively small quantities, that is under control of the person handling the bottle.

To facilitate an understanding of the invention I will confine the following detailed description to a simple, practical form of the invention and will describe it as applied to the ordinary or popular form of crown type.

In Fig. 1 of the drawings I illustrate a crown cap 10 applied to the neck 11 of a bottle, and I have shown the construction provided by this invention embodied in the cap 10. The neck 11 of the bottle is of the ordinary type having a bead 12 at its upper end to receive the crown cap 10. The crown cap 10 illustrated in Figs. 1, 3, 4 and 6 of

the drawings is formed of sheet metal and has a flat top 13 and a downwardly extending peripheral flange 14 crimped at 15 to grip the bead 12 of the bottle neck. The cap is provided with a washer 16, usually of cork or the like, to engage between the top 13 of the cap and the neck of the bottle to make a fluid tight joint or connection.

The cap 10^a illustrated in Fig. 2 of the drawings is a detachable type of crown cap in which the crimped portion 15^a of the peripheral flange carries a clamping band 17 operable by a clamping lever 18 to clamp the crimped portion 15^a onto the bead of a bottle. This is a common and well-known type of cap often used in place of the type of crown cap first described. The advantage of the detachable type of crown cap is that it may be removed and replaced on a bottle whenever desired and is tight on the bottle when applied thereto, whereas the first described type of crown cap cannot ordinarily be re-applied to a bottle when once removed.

The construction provided by my present invention includes, generally, a valve 20, a spout 21 in connection with the valve, and a plate 22 cooperating with the top of the cap to hold the valve 20.

In accordance with the preferred form of the invention the valve 20 is in the form of a ball valve, that is it is spherically curved, and its exterior or outer surface is finished so that it is truly spherical and smooth. The spout 21 is preferably straight as shown in the drawings, and is provided with a central longitudinal opening 23. In accordance with the invention, the opening 23 continues from the spout through the valve 20 so that it opens at the outer surface of the valve at a point diametrically opposite the spout 21. In accordance with the preferred form of the invention the spout 21 is formed integral with the valve 20, the spout 21 and valve 20 forming a unit which is extremely simple of formation and suitable for manufacture with automatic machinery.

The plate 22 is preferably a flat sheet metal part carried at the under or inner side of the cap top 13. In accordance with the invention the plate 22 is in the form of a disk, preferably a round disk, and the top 13 is recessed or countersunk as at 30 to receive the plate. In the preferred construction the recess 30 in the top 13 is formed by pressing the top into the form shown throughout the drawings so that the recess 30 corresponds in depth to the thickness of the plate 22. The plate seats or fits tightly in the recess so that its lower face 31 is flush with the inner or lower face 32 of the cap top 13. This forms a flat continuous face in the cap carrying the washer 16. Further, in accordance with the invention the plate is fitted tightly or made tight in the recess 30, for instance the top of the cap and the plate may be

shaped and proportioned so that the plate is made tight by being pressed into seated engagements in the recess 30. In the drawings I have shown the top 13 formed with a projection 35 at the edge of the recess 30. This projection is adapted to engage the peripheral portion of the plate 22 in a manner to grip and hold the plate in the recess.

The plate 22 and the top 13 of the cap cooperate to hold the valve 20. To this end a concave depression 40 is formed in the lower or inner side of the cap 10, while a corresponding depression 41 is formed in the plate 22 to form a chamber between the top 13 and plate 22 shaped to accurately receive the valve 20. This valve 20 being spherical in form, the depressions 40 and 41 are shaped so that they cooperate to form a spherical chamber to carry the valve. In the preferred arrangement the depressions 40 and 41 are located centrally in the cap, the depression 40 being formed by pressing the central portion of the top 13 upwardly, as shown throughout the drawings, and the depression 41 is formed by pressing the central portion of the plate 22 downwardly, as shown in the drawings.

The upwardly pressed part of the top 13 forming the depression 40 is provided with an opening 50 in the form of a slot which passes the spout 21. The spout 21 fits the slot 50 so that it can be moved a suitable distance, say, for instance, between positions such as are shown in Figs. 3 and 4 of the drawings, thus causing the valve 20 to be turned between the top of the cap and the plate 22. It will be apparent that the slot 50 can be proportioned to give the spout a large angular movement and that the particular direction of movement of the valve between the top 13 and plate 22 will be controlled by the configuration of the slot. In practice it is preferred to form a straight slot 50, as shown in Fig. 6 of the drawings, in which case the valve has a simple rocking or oscillating movement.

The downwardly depressed portion of the plate 22 forming the depression 41 is provided with an opening or port 53 adapted to register with the opening 23 extending through the spout 21 and valve 20 when the parts are positioned in a manner such as is shown in Fig. 4. In the preferred form of the invention the washer 16 is annular in form and the depressed portion of the plate 22 projects downwardly through the opening in the washer so that the port 53 has direct communication with the interior of the bottle and is not interfered with by the washer. With the arrangement of parts provided by the invention, the bottle is tightly sealed or closed when the spout and valve are positioned as shown in Fig. 3, while there is an opening into the interior of the bottle when the parts are positioned as shown in Fig. 4 the opening being through the port 53 and opening 51.

The present invention is intended to provide a construction commercially practical and capable of inexpensive manufacture. The parts cooperating to effect the seal, that is the plate 22 having the depression and the valve 20, may, when produced by inexpensive methods of manufacture, be more or less inaccurate, which inaccuracies might result in leakage.

10 The invention overcomes the difficulties that might thus arise through imperfect formation of parts, providing a plating or coating of material on one or both of the cooperating parts, for instance on the surface of 15 the depression 41 and/or on the surface of the valve 20. This coating is preferably a thin coating of a soft or conforming metal, it being preferred to use metal or metal alloy which will not corrode or be attacked by ordinary products. By thus coating the surface of the depression 41 and the outer surface of the valve 20, a tight sealing engagement is established between these parts when the device is assembled by tightly seating the 25 plate 22 in the depression 30 in the top of the cap. It is to be understood, of course that the parts are proportioned so that the valve 20 is gripped or clamped with more or less pressure between the plate 22 and top 13 30 holding the surface of the valve and the wall of the depression 31 in close or sealing engagement. It will be apparent that the coating of soft metal above referred to may be comparatively thin, it being necessary merely to compensate for slight imperfections or inaccuracies in the parts.

From the foregoing description it will be apparent that the present invention provides a construction that can be applied to a bottle 40 cap at very little cost and can be used commercially without interfering with capping devices ordinarily used in applying bottle caps. Further, it will be apparent that the device can be used on containers or bottles 45 carrying various products. In this connection it is to be pointed out that the proportioning of the parts, that is the size of the valve and the size of the opening 23 through the valve 20 and spout 21 may be varied, depending upon the character of the product 50 to be dispensed, it being apparent that in some cases a small opening will be required while in other cases a large opening will be required. In the former case the valve may 55 be comparatively small in diameter, while in the latter case it may be necessary to make a valve comparatively large in diameter. It is to be particularly noted that the invention 60 provides only two parts in addition to those ordinarily involved in a crown cap, namely the unit forming the valve and spout and the place which cooperates with the top of the cap to hold the valve and spout. These parts 65 are obviously simple and inexpensive in

formation making the device inexpensive of manufacture and commercially practical.

Having described only a typical preferred form and typical applications of the invention, I do not wish to limit myself to the specific details set forth, but wish to reserve to myself any changes or variations that may appear to those skilled in the art or fall within the scope of the following claims.

Having described my invention, I claim: 75

1. In combination, a bottle cap, a spherical valve, and a plate having a flange attached to the cap and a depressed part carrying the valve, the cap having a flat top with a recess holding the flange of the plate. 80

2. In combination, a bottle cap having a flat top with a recess in its inner side and a central depression in its inner side, a spherical valve, and a plate having a flat flange tightly carried in the recess and having a central depression cooperating with the depression in the top to carry the valve. 85

3. In combination, a bottle cap having a flat top with a recess in its inner side and a central depression in its inner side, a spherical valve having a projecting spout, and a plate having a flat flange tightly carried in the recess and having a central depression cooperating with the depression in the top to carry the valve, the top having an opening 90 passing the spout and the plate having an opening cooperating with an opening in the valve. 95

In witness that I claim the foregoing I have hereunto subscribed my name this 8th 100 day of November, 1928.

JOSEPH M. JENSEN.
